FLASHLIGHT CASING

Reuben B. Lambert, New Haven, Conn.

Application January 22, 1953, Serial No. 23,250

Term of patent 14 years

(Cl. D48—24)

To all whom it may concern:

Be it known that I, Reuben B. Lambert, a citizen of the United States, residing in New Haven, county of New Haven, and State of Connecticut, have invented a new, original, and ornamental Design for a Flashlight Casing, of which the following is a specification, reference being had to the accompanying drawing, forming a part thereof.

Fig. 1 is a side elevational view of a flashlight casing showing my new design.

Fig. 2 is a front end elevational view of the same.

I claim:

The ornamental design for a flashlight casing, substantially as shown.

REUBEN B. LAMBERT.
